UNITED STATES PATENT OFFICE

GEORG GUSTAV EMIL SCHMITT, OF BERLIN-WILMERSDORF, GERMANY

SWIMMING APPLIANCE

Application filed June 11, 1931, Serial No. 543,663, and in Germany April 23, 1931.

This invention relates to a swimming appliance of the kind comprising a glove to which a thrust plate is connected in a laterally extending position so as to enable the swimmer to obtain a better hold on the water.

In a known device of this kind the thrust plate is connected pivotally to the glove so that it can collapse on the hand being moved in the direction of the top surface thereof. 10 This arrangement has been found not only to be unnecessary, but actually disadvantageous without a skillful control of the hand movements.

To remedy this defect, the thrust plate is 15 according to the invention secured rigidly to the glove and maintained in a slightly downturned position relative to the palm of the hand.

Fig. 1 of the accompanying drawing represents a plan view of the device in position of 20 use,

Fig. 2 is an elevation of the thrust plate and its fastening strip, and

Fig. 3 is an inverted plan view of the device in operative position.

The glove *a* is provided with open-ended, webbed finger portions and is secured to the hand by means of a wrist strap *b*. Connected to the palm of the glove is a thrust plate *f* 30 which is maintained in a slightly downturned position relative to the palm, as indicated in Fig. 2. By this arrangement the thrust plate not only forms an additional bearing surface, but it also guides the water towards the hand 35 so as to offer greater resistance to the latter.

The thrust plate is connected to the glove either direct or through the medium of a separate fastening strip *e*. In the latter instance the strip *e* and plate *f* may be formed 40 with upturned flanges *e'* and *f'* respectively which may be riveted together. The angle *h* between the plate *f* and strip *e*, which is less than 180°, may be controlled by means of a wedge-shaped packing piece *g* inserted between the two flanges.

I claim:

1. A swimming appliance of the character described comprising a glove, and a thrust plate connected immovably to one side of 50 said glove in a laterally extending position

and maintained at an angle less than 180° to the palm of the hand.

2. A swimming appliance of the character described, comprising a glove, a metal strip connected to the palm of said glove and formed at one side of the glove with an upturned flange, and a thrust plate having a flange whereby it is connected to the flange of the strip and maintained at an angle less than 180° to the latter. 55 60

3. The swimming appliance claimed in claim 2 in combination with a wedge-shaped packing piece inserted between the flanges for fixing the angle between the plate and the strip. 65
